APPARATUS FOR ASSEMBLING ADJUSTABLE
SHOULDER STRAPS

Aaron Mendelsohn, Brooklyn, N. Y.

Application March 16, 1940, Serial No. 324,447

11 Claims. (Cl. 223—49)

The present invention relates to apparatus for assembling adjustable shoulder straps, of the type used for ladies' undergarments, which generally consist of a combination of buckles and tape or ribbon strap members.

It is the object of the present invention to provide apparatus of the character described having improved buckle supply and buckle feeding mechanisms whereby the feeding of the buckles to strap receiving position is made smoother and more certain.

Another object of the present invention is to provide apparatus of the character described having buckle feeding mechanisms of improved construction and operation.

Still another object of the present invention is to provide buckle guiding and feeding mechanisms which will arrange and keep the buckle in accurate register with the path of the strap inserting blades to thereby prevent the striking of the buckle frame by the blades.

A still further object of the present invention is to provide apparatus of the character described that may be used to assemble straps with pronged buckles of the type that engage the end of a strap and make unnecessary the stitching of the long strap member on the buckle.

A further object is to provide apparatus which makes possible the insertion and maintenance of the shorter strap in its associated buckle and keeping its ends together without any pre-stitching, until the same are sewn to a garment.

It is a still further object to provide apparatus of the character described which is of generally improved and simplified construction, which is relatively easier to operate, requiring relatively less operating power, and which is sturdy, durable and economical.

One embodiment of the apparatus of the present invention is shown in the accompanying drawings. It is to be understood, however, that the embodiment shown is by way of illustration only, to make the principles and practices of the invention more readily comprehensible to those skilled in the art and it is not intended in any way to limit its spirit or scope to the details of the embodiment shown.

In the drawings:

Fig. 1 is a view in side elevation of the embodiment of the apparatus of the present invention;

Fig. 2 is a top plan view of the same;

Fig. 3 is a view of a strap completely assembled by the apparatus of the present invention;

Fig. 4 is a fragmentary view in side elevation

and partly in section of the apparatus of the present invention;

Fig. 5 is a fragmentary front end view of the same; showing also a front view of the means for engaging the ends of one of the strap members during the assembly of the second strap member with the buckles.

Fig. 6 is a fragmentary section view taken on line 6—6 of Fig. 4;

Fig. 7 is a fragmentary sectional view taken on line 7—7 of Fig. 4; and

Fig. 8 is a fragmentary sectional view taken on line 8—8 of Fig. 4;

Fig. 9 is a fragmentary longitudinal sectional view taken on line 9—9 of Fig. 4; and

Fig. 10 is a fragmentary side elevational view of means for engaging the ends of one of the strap members while the second strap member is being assembled with the buckles.

Referring more specifically and in greater detail to the embodiment of the apparatus of the invention which is illustrated in the accompanying drawings, such apparatus comprises a table, including a base 10, which may be supported upon a work-bench 11, and the top 12, upon which is fixedly mounted an elongated rectangular bed plate 13, which may extend and overlie the rear edge of the table top 12.

The bed plate 13 is formed with a longitudinally disposed, slightly off-center, shallow buckle guiding channel or groove 14, to serve as a guide-way or track for the buckle 15, having the single eyelet 16.

The buckles 15 are supplied to the channel 14, from a hopper, designated generally as 17, and comprising preferably, a post or standard 18, mounted in upright position on the bed plate 13, to one side thereof and at a distance from its front end. The post or standard 18 is provided with a buckle receiving recess 19, in one edge, arranged to overlie the channel 14, and to discharge buckles 15, which may be stacked within the recess 19, one at a time, directly into the channel.

The hopper 17 is provided with a closure plate 20, having, preferably, an inspection slot 21, and which is held in place over the recess 19, by right angle guide members 22, which are fixed on the post 18.

A second hopper, generally designated as 25, is provided at the forward end of the bed plate 13, for supplying the second type of buckle 26, having two eyelets 27 and 28. This second hopper 25, comprises an upright post or standard 29, fixed on a block 30, arranged at the forward

end of the bed plate 13, flush with the edge thereof. The standard 29 is provided with a vertically disposed forwardly facing buckle housing recess 31, so arranged that one of the buckle eyelets such as 27, will be in vertical register with the eyelet 16, of a buckle 15, when the two buckles are in vertical alignment. The second hopper 25 is also preferably provided with a closure member 32, having an inspection slot 33, and held in place by right angle guide members 34, mounted on the standard 29.

The block 30 is provided with a longitudinally disposed buckle guideway, channel or groove 35, in its upper surface, which groove is in register with the recess 31, to receive buckles therefrom. The rear portion of such channel or groove, 35, is preferably of a width slightly less than the recess 31, or the buckle 26, contained therein with that part of the channel 35 extending forwardly from the rear face of the magazine recess 31, having offset edges as at 36, to provide a width sufficient to accommodate a buckle 26 in width and thickness. A rectangular slide bar 37 is disposed within the channel 35, which bar may be formed to have its front end reduced by the thickness of a buckle to provide a shoulder 38, which may engage a buckle resting on the reduced portion of the bar 37, for movement forwardly within the guideway 35.

In order to snugly accommodate the buckles within their respective hopper recesses, regardless of any minor variations in their size, there are provided means such as are illustrated in association with the hopper 25, consisting of plates 39, arranged along the opposed sides of the recess 31, and resiliently urged toward one another, as by means of wire springs 40, arranged in slots or recesses 41, formed in the sides of the post or standard 29, or in the face of the block 30, as may be desired, which springs are held in place by screws 42, set into the face of the standard 29. It will be readily understood that a similar arrangement of resiliently pressed plates may be provided in connection with the hopper 17.

To present the buckles in operating position, their respective guideways or channels are continued in a plate 43, secured to the forward face of the block 30, by set screws 44. The plate 43 has a cut-out portion 45, along its upper edge in position to permit reciprocation therethrough of the rod 33 and with a second cut-out portion 46, on its lower edge surrounding the end of the channel 14.

Extending forwardly and horizontally from the upper edge of the plate 43, from each side of the cut-out 45, are a pair of spaced parallel bars or fingers 47, separated a distance slightly less than the width of buckle 26, and provided with facing grooves 48, which are in alignment with the surface of the reduced end of the rod 33, and which serve as continuation of said surface, forming tracks for the edges of the buckles 26.

A similar set of bars or fingers 49, is provided on the lower edge of the plate 43, one along each side of the cut-out 46; the bars 49, being provided with facing grooves 50, to accommodate and guide the edges of the buckle 15, as it is moved out of the channel 14.

In order to move the buckles 15 to operating position there is arranged within the channel 14, to the rear of the hopper 17, a sliding blade 51, held in place by plates 52, resting on the edges of the work plate 13, and partly overhanging the edges of the channel 14. Fixedly mounted adjacent the rear end of the sliding blade 51, is

a block 53 which is guided intermediate the guide bars 54, arranged above the plates 52.

A pin 55, is set into the base of the block 53, which serves to engage one end of a wire chain or belt 56, which is passed over a pulley 57, set into the side of the block 30, through an opening 58, in the work bench and under and over pulleys 59 and 60, respectively, the other end of the wire or belt 56, being engaged on a treadle 61, which is pivoted on a bracket 62 which is fixed on a floor or the like.

It will be apparent that pressure on the treadle will cause movement of the sliding blade 50, forwardly in the groove 14, to engage a buckle 15, and to move it forwardly in the guideway or channel 14, and in the grooves 50 of the fingers, 49.

It will be readily understood that the size and arrangement of parts just described are such that at the end of the stroke of the blade 51, the buckle 15 will be brought to operating position.

In order to automatically return the blade 50 to its initial position and thus permit a second buckle 15, to drop into the channel 14, to be moved in its turn to operating position upon repeated actuation of the treadle, there is set into the channel 14, to the rear of the blade 51, a rearwardly extending bar 63, upon which is fixed a pin 64, to which is anchored one end of a blade returning coil spring 65, the other end of which is secured to the pin 55, arranged on the block 53.

Means may be provided to limit and cushion the return stroke of the blade 51, which may consist of a U curved leaf spring 67, fixed on a slotted plate 68, alongside the guideway 14, which may be adjustably secured to the bed plate 13, by means of a thumb screw 69, passing through the slot 70, into the bed plate 13; and of a plate or bar 71, transversely disposed in block 53, the edge of which is adapted to abut against spring 67, to limit rearward movement of the blade 51.

In order to advance a buckle 26, to operative position, the rod 37, on the reduced portion of which the buckle is deposited, by gravity, is provided in its rear end with an aperture 72, in which is seated and held by a set screw 73, the end of one leg of an L shaped rod or pin 74, the other leg of which extends rearwardly and parallel to the rod 37, avoiding the hopper 11, and is guided and supported in an aperture 75, in the bracket 76, fixed on the work table 13. Adjacent its free end, the L shaped member is provided with a sideways extending pin 77, to which is attached one end of a coil spring 78, the other end being held on a vertical pin 79, set into the work table, which spring 78, normally maintains the rod in retracted position.

The plate 71, which is fixed on the block 53, is provided with a vertically offset portion 80, on which is fixed, adjustably, by set screw 81, a slotted member 82, having an offset part 83, which is adapted to engage the free end of the L shaped rod 74 to move it and the rod 37 forwardly in the apparatus, after the slide 51 has been moved a short distance. The delayed start of the moving mechanism for the buckle 26, relative the movement of the blade 51, makes operation of the apparatus relatively easier for the reason that such movement occurs after momentum has been gathered by the moving mechanisms.

The post 29, is provided with a pair of spaced brackets extending forwardly from one of its sides, consisting of an upper bracket 85, and a lower bracket 86, each having an offset enlarged head 87, and 88, respectively, which are provided

with vertically aligned openings 88 and 89, respectively, to receive and guide a rod or plunger 91. The lower end of the plunger 91 is slotted to receive one end of a hook ended blade 92, and a relatively longer, blunt ended blade 93, which are removably and adjustably held in place by set screws 94.

The plunger 91, is provided along its center portion with a vertically disposed slot 95, through which passes a horizontally disposed operating pin 96, set in a collar 97, which is adjustably held on the plunger by a set screw 98. The collar 97 is normally maintained against the underside of the upper bracket head 87, in position to hold both of the blades 92 and 93, above the upper buckle guideway, by means of an expansion spring 99, mounted about the plunger 91, intermediate the upper face of the lower bracket head 88, and the underside of the collar 97.

A second pin or screw 100, is set into the lower bracket head 88 and also passes through the slot 95 to limit the upward movement of the plunger 91.

The plunger 91 is operated by a cable 101, attached to the sideways extending pin 96 by one of its ends, its other end engaging the free end of a treadle 102, pivoted on the bracket 62.

I have found that, in practice, the positioning and aligning of the buckles with the reciprocal blades cannot always be accurately accomplished even with a properly adjusted buckle moving mechanism for the reason that, frequently, the buckles are projected, by momentum past the line of movement of the blades or, at other times, have a tendency to be retracted. Such occurrences result in the damage or spoiling of the buckle, on occasion after part of the assembly has been accomplished, causing a waste, both of time and money. Frequently, also, the buckles may become disarranged due to the manual handling of the straps partly passed therethrough with the same detrimental results.

I have therefore devised means for positively receiving and retaining buckles in properly aligned position. Such means comprises a resilient seat into which the buckle may be easily moved and from which it may be easily removed, but which prevent accidental movement of the buckles. Such seats are illustrated in Fig. 9, of the drawings and may comprise a pair of spring members 104, each having a curved portion 105, formed to fit about and seat one side of a buckle. One of such spring members 104 is arranged in a slot or recess 106, formed in each of the forwardly extending bars or fingers, 47 or 50, as the case may be and is suitably secured by one end, as by a set screw 107 to its respective bar or finger.

In operation, the treadle 61 is pressed to move buckles 15 and 26 into operative position. A shorter ribbon or band 108 is then placed above the lower buckle 15 and the treadle 102, pressed down to bring the blade 93, through the eye 16 of the buckle 15, carrying the ribbon 108 with it, in a loop. One end of the ribbon is then pulled through the eye 16 and the two ends are thus juxtaposed and engaged by means which will hereinafter be described, out of the way of the further operations. The end of the longer band or ribbon 109 is then placed over the upper buckle 26 and firmly held by the operator as the treadle 102 is pressed again to pass the band or ribbon 109 through the eye 27 of the buckle 26 and the eye 16 of the buckle 15. The free end of the ribbon 109 is then pulled through the eye 16 and is engaged upon the hook end of the blade 92,

which draws it upwardly through the eye 28 of the buckle 26 as the treadle 102 is released. The end of the ribbon 109, held by the operator, is then drawn out to leave only a short ribbon end projecting upwardly through eye 28 with the longer end projecting through eye 27. The short end is then placed over and pushed through eye 27, by pressing blade 93 downwardly. The longer end is subsequently placed over and pushed and drawn through eye 28, completing the assembly, and the assembled strap manually removed from the apparatus.

In order to prevent displacement of the short ribbon 108 from the buckle 15, during the interlacing of the longer ribbon, there are provided means for engaging its juxtaposed ends, which means may comprise a spring clamp 110 extending forwardly from the work table 12, between whose spring members the ribbon ends may be slipped and held, or of a sharp ended pin 111, mounted vertically upon the forwardly extending leg 112 of an L shaped bracket 113, secured to the work table, upon the point of which the ribbon ends may be pinned.

In order to avoid the necessity of stitching the ends of the ribbon 108 together, an operation now required to prevent disassembly during handling of the assembled strap prior to attaching it to a garment, which may be a long time after the strap is assembled, I prefer to employ for the above purpose a pin 111 which is provided with an eye 114 adjacent its free upper end. A thread 115 is drawn through the eye 114 and both of its ends permitted to fall. A plurality, such as a dozen of pairs of ends of ribbons 108 may then be stuck over the end of the pin 111 and the doubled over thread 115. One end of the thread 115 is then pulled out of the ribbon ends, and the ribbons removed from the pin, remaining strung on the thread which may then be tied, for safety.

In practice, two types of buckles 26, are used, one with a prong 116 projecting from the center bar 117 into eye 27 and one in which the eye 27 is unobstructed. Where a pronged buckle is used, it engages the ribbon end 108 to prevent its slipping out and avoids the need for stitching the end 108 to its immediately adjacent ribbon fold, as must be done when an unpronged buckle is used. Heretofore, no apparatus was known for assembling straps with pronged buckles. In the present invention, however, I have devised apparatus capable of utilizing pronged buckles 26 and have made this possible by providing the blade 93 with a recess 119, which may be either a slot, or a groove, as shown, extending longitudinally of such blade, which will permit reciprocation of the blade through eye 27, without interference from the prong 116.

What I claim as my invention is:

1. In apparatus of the character described, a lower buckle guideway, a spacing member arranged over the forward end of the said lower guideway, a second buckle guideway on the upper surface of the said spacing member, a gravity feed buckle hopper arranged on the lower guideway to the rear of the spacing block and a second gravity feed buckle hopper arranged over the said second guideway on top of the said spacing member.

2. In apparatus of the character described, a pair of spaced apart parallel buckle guideways, buckle moving slides arranged in each of said guideways, means for moving one of said slides and mechanism for interengaging the said

slides to move the second of said slides after movement of the first slide has commenced.

3. In apparatus of the character described, a pair of superposed, parallel, spaced apart buckle guideways, the upper of said guideways being of lesser length than the lower guideway, buckle moving slides arranged in each of said guideways, means for movably engaging the lower of said slides to feed a buckle to operative position and mechanism for interengaging the two slides after movement of the lower slide has commenced, to move the said upper slide for feeding a second buckle to operative position.

4. In apparatus of the character described, having a lower buckle guideway, a spacing member arranged over the forward end of said lower buckle guideway and a second buckle guideway of lesser length than the said lower guideway over the said spacing member, a plate secured to the forward face of the spacing member, said plate having two pair of parallel, forwardly extending fingers, each pair of forwardly extending fingers having facing grooves forming a buckle guideway, continuous with one of said first named buckle guideways, a gravity feed buckle hopper arranged over each of said guideways, one to the rear of the other, and means for moving a buckle simultaneously along each of said guideways.

5. Apparatus of the character described, comprising a lower buckle guideway, a spacing member arranged over the forward end of said lower buckle guideway, a second buckle guideway over the said spacing member, a plate secured to the forward face of the spacing member, said plate having two pair of parallel, forwardly extending fingers, each pair of forwardly extending fingers having facing grooves forming a buckle guideway, continuous with one of said first named buckle guideways, a slot in each of said fingers adjacent the operative position for the buckle and resiliently a mounted member having a seat for one side of a buckle arranged in each of said slots and adapted to receive the side of a buckle and retain it in operative position.

6. In apparatus of the character described, a pair of spaced parallel superposed buckle guideways, gravity feed buckle hoppers arranged over each of said guideways to feed buckles thereto, one forwardly of the other, a pair of brackets on the foremost of said hoppers, each of said brackets having an aperture in alignment with the other, a plunger having a longitudinally disposed slot arranged within the said apertures, a

collar adjustably fixed on the said plunger, intermediate the said brackets, a spring about the said plunger intermediate the said collar and the lower of said brackets, a pin set into one of said brackets, passing through the said slot, to prevent rotation of the plunger within the brackets, and strap engaging blades removably set into the lower end of said plunger.

7. In apparatus of the character described having a gravity feed buckle hopper, a plate arranged within the hopper along one wall thereof, and resilient means arranged adjacent the lower end of said plate for urging the plate away from said wall to provide a snug outlet for the buckles within the hopper.

8. In apparatus of the character described, a frame having a pair of buckle guideways fixed thereon in spaced apart relation to one another, and a gravity feed buckle hopper arranged above each of said guideways one to the rear of the other to supply buckles to the guideways, buckle holding jaws at the end of each of said guideways, and means for moving a buckle from each of said hoppers simultaneously to its respective buckle holding jaw.

9. In apparatus of the character described, a frame having a pair of spaced apart parallel, superposed buckle guideways fixed thereon and a gravity feed buckle hopper arranged above each of said guideways one to the rear of the other to feed buckles thereto, buckle holding jaws at the end of each of said guideways, and means for moving a buckle from each of said hoppers to its respective buckle holding jaw.

10. In apparatus of the character described, a frame having a pair of spaced apart parallel guideways fixed thereon, one of said guideways being of lesser length than the other and a gravity feed hopper arranged over each of said guideways, one to the rear of the other to supply buckles to the guideway and means for moving a buckle simultaneously along each of said guideways.

11. In apparatus of the character described, a frame having a pair of spaced apart parallel, superposed buckle guideways fixed thereon, the upper of said guideways being of lesser length than the lower and a gravity feed buckle hopper arranged above each of said guideways to supply buckles thereto and means for moving a buckle simultaneously along each of said guideways.

AARON MENDELSONN.
